UNITED STATES PATENT OFFICE.

WILLIAM H. VON SWARTWOUT, OF NEW YORK, N. Y.

DESIGN FOR SOCIETY EMBLEM, FLAG, BANNER, &c.

SPECIFICATION forming part of Design No. 12,230, dated April 19, 1881.

Application filed March 10, 1881. Term of patent 3½ years.

To all whom it may concern:

Be it known that I, WILLIAM HENRY VON SWARTWOUT, a citizen of the United States of America, residing in the city, county, and State of New York, have invented and produced a new and original Design for an Ornamental Decoration or Emblematical Array for Banners, Tapestry, Society Emblem, Flags, Badges, Statues, Statuettes, and analogous purposes, reference being had to the accompanying illustration, of which the following is a specification.

This design is intended to be used as a whole for ornamental tapestry or covering of walls, stained-glass windows, as a transparency, or for similar purposes to which it is adaptable; and its constituent elements may be used for various distinct purposes, as will readily be perceived by referring to the illustrations.

Figure 1 is a front view of the design as a whole, which may be printed or painted on cloth, paper, glass, canvas, walls, or other material; embroidered, woven, stamped, embossed, or otherwise wrought into silk, cloth, paper, or other substances; worked or molded in glass, gold, silver, bronze, or other metals, marble, clay, plaster, or other suitable material—as, for example, tapestry, banners, flags, screens, and articles where ornamentation and representation (such as in tableaux, the drama, &c.) is the main object. The distinctive features of this design are intended to be used and manufactured either together or separately.

2 is the allegorical figure of a woman, representing "Columbia," in a new costume, as a goddess of peace and liberty, her sandaled feet standing upon America (which is uppermost) on the top of a globe. On her brow is a diadem of six-pointed stars, the center one being eight-pointed. In her right hand is an olive-branch, pointing toward her left, in which she holds the staff of a banner, which partly conceals the forearm and the hand. On her breast is a full sun, in the center of which is the word "Peace." The lower part of her dress (which is intended to be white) is edged with six-pointed stars. The edging or border of her dress (which is intended to be of red on the outside and blue on the inside, leaving a white stripe in the center) is to be dotted, or filled with six-pointed stars. Depending from the waist in graceful folds is a wide scarf or flag adorned with stars, borders, &c.

3 represents a banner on the upper part of the face of which is the representation of a blazing sun, containing in its center the words "The Truth," (which may be omitted and other words or a face substituted,) intended to be in a blue field, spangled with fourteen six-pointed stars, although the same may be increased or diminished in number without materially changing the design. Below the sun is a representation of the Western Hemisphere of the earth, and in the act of descending from the sun thereto are two doves, designed to be white. The banner is intended to have a double border or edging, the outer band of which is to be red and the inner one white. At the bottom is to be a fringe of gold, with tassels at the corners, if desired. The banner is suspended from a pole by cords with tasseled ends, the pole resting on the globe, being surmounted by a dove (which is to be white) or a star. The details may be slightly varied from without departing from the main character of the design.

4 represents a shield, (which may also be used separately as a society-badge,) composed as follows: The main portion has two rows of edging, same as described in the banner. In the center, within concentric circles, on what is to be a blue ground, (when colors are used,) are six-pointed stars, thickly set, surrounding a blazing sun. In the center of the sun are the words "Love and Truth," which may be omitted and other words or a face substituted without changing the character of the main design. To exemplify the use of which the shield is intended are inscribed thereon as follows: Above the sun is the word "Columbia's," and below the sun are the words "New University Society;" but said words, or any of them, may be changed to "The New Columbia University Peace Society," or be omitted, or other words substituted. The shield depends from a hemisphere bearing numerals and surmounted by a dove (which is intended to be white) with an olive-branch in its beak.

5 represents a flag (here shown as drooping to the right) with a double border, the same as that mentioned in the foregoing description of the banner and shield. On what is intended to be a blue field, surrounded with fourteen six-pointed stars. (which number, however, is not arbitrary, but may be diminished or increased at will,) is a full blazing sun, (intended to be golden, and may be embroidered, printed, painted, or otherwise represented thereon.) The word "Peace" is shown in the center of the sun; but this may be changed and any other words, a face, or a blank be substituted. The flag-staff, to which the flag is attached by rings, is surmounted by a star, which may be changed to a dove. This flag may also be used separately. Across and behind the said peace-flag is the United States national or war flag, the stars and stripes drooping to the left, and attached in like manner to a staff provided with a spear-head, which also may be changed to an eagle. This national or war flag is represented as stained or dripping with blood and torn through the stars. The flags are crossed in front of the globe. Behind the flags, as also behind the globe, clouds are shown, and behind all are rays of light, as from the sun shooting upward.

25 What I claim as my invention, and desire to secure by Letters Patent, is—

1. The allegorical representation 1 of a diademmed goddess standing upon a globe, with an olive-branch in her right hand and holding 30
a banner in her left, and arrayed in a flowing dress, the globe, the shield and its contents,
and the dove, the banner, and the flags, arranged substantially as shown and described.

2. The statue-like representation of a goddess, 2, holding the banner, combined and arranged as shown and described. 35

3. The banner 3, with the devices thereon, arranged as shown and described.

4. The shield 4, with its necessary contents 40
and accessories, including the dove, all combined and arranged substantially as shown
and described.

5. The peace-flag 5, substantially as shown
and described. 45

6. The flag 6, showing the rent between the stars and stained and dripping with blood, substantially as shown and described.

DEPARTMENT OF THE INTERIOR,
UNITED STATES PATENT OFFICE,
Washington, D. C., October 4, 1881.

Whereas, William H. Von Swartwout has, in writing, refused to receive Letters Patent No. 12,230, issued to him April 19, 1881, for a design for a "Society Emblem, Flag, Banner &c.," on the ground that the said Letters Patent were erroneously issued for three and one-half years only, instead of fourteen years, as petitioned, and whereas, upon a careful consideration of the record of the case, the facts constituting the ground of refusal are found to be correctly stated; it is hereby ordered that said design Letters Patent No. 12,230, be returned to the file and marked "canceled," and that Letters Patent in due form for the term of fourteen years be granted to said William H. Von Swartwout, pursuant to the record in the case.
